UNITED STATES PATENT OFFICE.

WALTER W. ROBERTS, OF SEATTLE, WASHINGTON.

AERIAL-NAVIGATION MACHINE.

996,366.

Specification of Letters Patent. Patented June 27, 1911.

Application filed September 16, 1910. Serial No. 582,366.

To all whom it may concern:

Be it known that I, WALTER W. ROBERTS, residing at Seattle, in the county of King and State of Washington, have invented a new and Improved Aerial-Navigation Machine, of which the following is a specification.

My invention relates to the art of aerial navigation and particularly of that type of air ships of the heavier than air variety, and more specifically it relates to the helicopter type of aerial navigation machines.

The invention has for its object to provide an improved construction of elevating and sustaining propeller mechanism whereby to obtain a greater efficiency in lifting power, and it also includes certain improvements in the general construction of machine and the manner of controlling the same.

In its more subordinate nature, the invention also resides in those novel details of construction, combination and arrangement of parts, all of which will be first described in detail, and then be specifically pointed out in the appended claims, reference being had to the accompanying drawings, in which:—

Figure 1, is a perspective view showing my machine in flight. Fig. 2, is a central, vertical, longitudinal section of the machine. Fig. 3, is a detail perspective view of a part of the machine. Fig. 4, is a detail horizontal section on the line 4—4 of Fig. 2. Fig. 5, is a detail horizontal section on the line 5—5 of Fig. 2. Fig. 6, is a detail perspective view of a part of the lifting and sustaining propellers, a part of the propeller coverings being removed.

Referring now to the accompanying drawings in which like numerals and letters indicate like parts in all of the figures, the main or keel frame is composed of suitable longitudinal bars 1—1 and 5—5, cross braced by cross bars 2—2 and 6—6 and vertical brace bars 7—7. The keel frame also includes a pair of longitudinal bars 3—3 on which a shiftable aviator's seat 4 is mounted.

The engine 8, which may be of any approved shape or construction, is mounted at

the forward end of the machine on the keel frame.

A bracket 9 may be provided with bearings 10 in which the shaft 11 of the propeller 11^a may be mounted. The propeller 11^a is preferably used to drive the machine in its movements forwardly and may be driven through gears 12 from the engine shaft 13.

The engine 8 is provided with the usual fly wheel 14 and in order that its speed may be controlled a suitable strap brake 17 is provided which is operated through the medium of a controlling wheel 16 and brake applying devices 15 in any approved manner. It should also be understood that the engine speed is controlled in the usual manner, as by advancing the spark, varying the compression, or any other method used in practical gasoline engine operation and the strap brake 17 is used for very close regulation as would be needed in starting and landing.

Mounted on suitable supports 18 are levers 20 that are pivoted on the supports at 21 and carry the traction wheels 19, buffer devices 22 being provided to absorb the shock, as will be readily understood by reference to Figs. 1, 2 and 3 of the drawings.

23 is a direction rudder which is hinged 80 on the vertical axis and has a crank 24 to which the connecting rod 25 is fastened, the rod 25 connecting with the rudder controlling lever 26 that is mounted adjacent to the aviator's seat 4. The lever mechanism 85 26 may be of any approved type and the illustration thereof is merely a suggestion.

27 is the altitude rudder which is hinged on a horizontal axis at the rear of the machine beneath the direction rudder 23 and 90 the altitude rudder 27 is provided with a crank 28 which is joined through a connecting rod 29 with the controlling lever 30 of any desired type. It will be observed that the rudder 23 is bevel cut at 23^a on its under 95 surface to allow the rubber 27 to be moved upwardly a sufficient distance to sustain the forward flight.

31 is what I term a compensating rudder which is mounted on a longitudinal hori- 100

zontal axis and is provided with a crank 32 which is connected through transmission rods and cranks 33—34—35 with a controlling lever 36 of any desired type.

5 37 and 38 are main bearings mounted in the keel frame to sustain the vertical propeller shafts.

The shaft 39 has a bearing in the lower one of the main bearings 37 and carries a 10 rigidly secured gear 40 that meshes with a pinion 13^a on the engine shaft whereby the motion of the engine shaft will be imparted to the shaft 39, ball bearings 41 being provided between the gear 40 and the bearing 15 37 and ball bearings 42 being provided between the gear 40 and the hollow propeller shaft 43. The shaft 43 turns on shaft 39 and carries a rigidly secured gear 44 which also meshes with the pinion 13^a to cause the 20 shaft 43 to rotate in a direction opposite to the direction of rotation of the shaft 39, ball bearings 45 being provided between the gear 44 and the upper main bearing 38, as clearly indicated in Fig. 2 of the drawings.

25 Secured to the hollow shaft 43 are rigidly mounted flange sleeves 46—47 which support the lower one 48 of the sustaining and elevating propellers. The propeller 48 is composed of a horizontal bottom plate 49 to 30 which the vertical vanes 50 are secured, the vanes 50 having their inner edges curved in the direction of movement of the propeller and their outer lower edges 52 curved downwardly and opposite to the direction of 35 movement of the propeller, as best shown in Fig. 6 of the drawings. The vanes 50 have their upper edges curved and covered by a covering 53, thereby making the propellers 48 of an umbrella type, leaving, however, a central opening 55 through which 40 the upper air may pass to the vanes 48 and to discharge them beneath the same. The plate 49 and vanes 50 with the covering 53 are sustained by crossed rods 54 which connect the same with the sleeves 46—47, as is clearly shown in Figs. 2 and 5 of the drawings.

56 and 57 are sleeves similar to those 46 and 47 and the sleeves 56 and 57 are pinned 50 or otherwise rigidly secured to the shaft 39 above the sleeve 47 and these sleeves 56 and 57 sustain the upper one 58 of the raising and sustaining propellers. The construction of the propeller 58 is precisely the same 55 as that of the propeller 48, excepting in lieu of a bottom plate the propeller 58 includes a ring plate 59, the vanes 60 having an inner edge 61 bent in the direction of movement of the propeller and the outer lower edges 62 curved in a direction opposite to the movement of the propeller, while a covering 63 similar to that 53 is provided and the crossed supporting rods 64 connect the sleeves 56—57 with the vanes 60 and ring

plate 59 of the propeller 58. The propellers 65 48 and 58 differ from one another further in that they are designed to turn in opposite directions, thus the turning effect on the machine of one of the propellers is effectively counteracted by the turning effect of the other propeller. The propeller 58 has a central passage 65 registering with that 55 of the propeller 48. The fuel for running the engine may be carried in a tank 66 and piped up by pipes 67 to the engine in any 70 approved manner. To operatively connect and disconnect the propeller from the engine a clutch mechanism 68 is provided.

So far as described, the manner in which my invention operates is as follows: The 80 machine being on the ground and it being desired to start it in flight, the engine 8 is set into operation in the usual manner, thereby setting the shafts 39 and 43 into motion, the shafts 39 and 43 turning in opposite directions and causing the respective propellers 48 and 59 to correspondingly turn. By reason of the construction of the propellers 48 and 58 the air will be drawn down through the openings 65 and 55 and 85 forced out between the rings 59 and covering 63 and the ring 49 and covering 53 in the direction of the arrows on Fig. 2, thereby exerting a lifting effect on the machine. The compensating rudder 31 is adjusted in 90 order to prevent turning of the machine should the torsional effect of the turning of one propeller 48 or 58 exceed that of the other. Having arrived at the desired elevation, the speed or rotation of the propellers 48 and 58 is so adjusted as to maintain the machine at the altitude desired, after which the clutch mechanism 68 is 100 operated to throw the forward propeller 11^a into action. The machine is thereby 105 driven forward, the direction of flight being controlled by the rudder 23 and by manipulating the rudder 27 the machine may be made to ascend or descend without changing the speed of action of the propellers 48 and 58, save when making a landing. When 110 it is desired to make a landing the speed of the propellers 48 and 58 is cut down as rapidly as necessary as the machine approaches *terra firma*. By combining the action of the propellers 48 and 58 with that of rudder 27, the elevating and descending control of the machine may be rendered 115 practically perfect and all danger of the machine turning turtle is practically eliminated. Furthermore, should the propellers 48 and 58 cease their turning for any cause while the machine is in the air, their umbrella shape will act as a parachute and break the fall of the machine to a considerable degree. If desired, the propeller 11 may be omitted and the machine propelled 120 forwardly by permitting the keel frame of 125

the machine to tilt downward at the forward end so that the shafts 43-49 will tilt forwardly and then speeding up the engine sufficiently to prevent the machine from 5 gliding downward. The equilibrium of the machine is further aided by the gyroscopic action of the propellers 48 and 58.

From the foregoing description, taken in connection with the accompanying drawings, it is thought the complete construction, 10 operation and advantages of my invention will be readily apparent.

Having thus described my invention, what I claim is:

- 15 1. In a flying machine, a keel frame, a pair of oppositely rotatable propellers mounted on a vertical axis in said keel frame, a motor geared with said propellers for effecting their rotation in opposite directions, each of said propellers including a plurality of radial vanes, umbrella-like coverings over said vanes, each of said propellers having a central opening, and a closure plate carried by the lowermost propeller beneath its central opening.
- 20 2. In an aerial navigating machine, a keel frame, a pair of propellers mounted on a common axis in said frame, means for effecting opposite rotation of said propellers, each 25 of said propellers including radial vanes, umbrella-like coverings over said vanes, each of said propellers having a central passage, the uppermost propeller including a ring plate carried beneath said vanes and of less diameter than the periphery of said propeller to leave a space between said ring plate and the periphery of the propeller, the lowermost propeller having a bottom plate secured beneath said vanes, the diameter of 30 which is less than the diameter of the periphery of the respective propeller to leave a space between said bottom plate and the periphery of said propeller, substantially as shown and described.
- 35 3. In a flying machine, a keel frame, a pair of oppositely rotatable propellers mounted on a vertical axis in said keel frame, a motor geared with said propellers for effecting their rotation in opposite directions, each of said propellers including a plurality of radial vanes, umbrella-like coverings over said vanes, each of said propellers having a central opening, and a closure plate carried by the lowermost propeller beneath 40 its central opening, said vanes having their ends against which the air enters curved in the direction of rotation of the propeller, and their ends from which the air leaves curved in a direction opposite to the direction of rotation of the propeller.
- 45 4. In an aerial navigating machine, a keel frame, a pair of propellers mounted on a common axis in said frame, means for effecting opposite rotation of said propellers, each 50 of said propellers including a plurality of radial vanes, umbrella-like coverings over said vanes, each of said propellers having a central opening, and a closure plate carried by the lowermost propeller beneath its central opening, said vanes having their ends against which the air enters curved in the direction of rotation of the propeller, and their ends from which the air leaves curved in a direction opposite to the direction of rotation of the propeller.
- 55 5. In an aerial navigating machine, a keel frame, a pair of oppositely rotatable propellers mounted on a common axis in said frame, means for effecting opposite rotation of said propellers, each 60 of said propellers including a plurality of radial vanes, umbrella-like coverings over said vanes, each of said propellers having a central opening, and a closure plate carried by the lowermost propeller beneath its central opening, said vanes having their ends against which the air enters curved in the direction of rotation of the propeller, and their ends from which the air leaves curved in a direction opposite to the direction of rotation of the propeller.
- 65 6. In an aerial navigating machine, a keel frame, a pair of oppositely rotatable propellers mounted on a common axis in said frame, means for effecting opposite rotation of said propellers, each 70 of said propellers including a plurality of radial vanes, umbrella-like coverings over said vanes, each of said propellers having a central opening, and a closure plate carried by the lowermost propeller beneath its central opening, said vanes having their ends against which the air enters curved in the direction of rotation of the propeller, and their ends from which the air leaves curved in a direction opposite to the direction of rotation of the propeller.
- 75 7. In an aerial navigating machine of the helicopter type, a keel frame, a power plant mounted on said keel frame, main bearings mounted on said keel frame, a duplex shaft mounted in said bearings, raising and sustaining propellers mounted on said duplex shaft, transmission gearing between said

power plant and said duplex shaft for effecting a rotation of said propellers in opposite directions, the upper of said propellers having an open ended central passage, the lower one of said propellers having a central passage in communication with the central passage of the upper propeller and a closure plate for closing the lower end of said cen-

tral passage, each of said propellers including radial vanes and an umbrella-like covering over said radial vanes. 10
